John F. Anderson

UNITED STATES PATENT OFFICE.

JOHN F. ANDERSON, OF SAN FRANCISCO, CALIFORNIA.

DESIGN FOR AN AUTOMOBILE DIRECTION AND STOP SIGNAL.

56,048.

Specification for Design.

Patented Aug. 10, 1920.

Application filed September 30, 1919. Serial No. 327,606. Term of patent 14 years.

To all whom it may concern:

Be it known that I, JOHN F. ANDERSON, a citizen of the United States, residing at San Francisco, in the county of San Francisco and State of California, have invented a new, original, and ornamental Design for Automobile Direction and Stop Signals, of which the following is a specification, reference being had to the accompanying drawings, forming part thereof.

The figure is a face view of my design for automobile direction and stop signal with both of the signal arms extended.

As shown by the drawings the leading and material feature of my design consists

of the two oppositely arranged ornamental dart pointed hollow signal arms—the artistic case for sheltering them and keeping them normally out of vision, and the ornamental top, all as shown by the drawings.

Having described my invention, what I claim as new, and desire to secure by Letters Patent, is—

The ornamental design for an automobile direction and stop signal as herein shown and described.

JOHN F. ANDERSON.
